UNITED STATES PATENT OFFICE

2,113,849

CONTROLLED VALVE

Nathan Marcus, Union City, N. J.

Application May 6, 1936, Serial No. 78,145

1 Claim. (Cl. 236—18)

This invention relates to control devices for valves for hot-water systems, particularly where steam is used for heating water in a reservoir, tank or container, and the main object of my invention is to provide automatic control means for the temperature of the water in the tank through the control of a combined intake and exit valve in a novel, practical and efficient manner.

Another object of my invention is to provide an electrically operated control means for a valve like the one indicated hereinbefore, said means being controlled by thermostat device in the hot water reservoir itself.

Still a further object of my invention is to provide a device as characterized hereinbefore where the incoming heating medium will be controlled through the valve but an exit of the used medium from the tank or other heating system will be permitted all the time.

Other objects of the invention will be apparent as the specification of the same proceeds, and among others I may mention: to provide a controlled device as indicated, which will be simple in construction, mainly built up of standard parts, easily available, which will be quick and reliable in operation, will be easy to install and will be comparatively inexpensive to manufacture.

In the drawings forming a part of this specification and accompanying the same:

Fig. 1 is a diagrammatical view showing a heating system with a hot water tank to which my invention has been applied;

Fig. 2 is a front diagrammatical detail showing the arrangement of my device from a room distant from the hot-water tank to be controlled;

Fig. 3 is a fragmentary sectional detail showing the application of my valve to a hot-water tank and the electrical control and operating means for said valve, while

Fig. 4 is a front view of the same detail, and

Fig. 5 is a fragmentary section at the portion of the hot-water tank wall where an aquastat is secured therein.

Referring now to the drawings more closely by characters of reference, the numeral 10 indicates the hot-water tank or reservoir of any usual construction, here a cylindrical one being shown, which may be fed by cold water through the pipe line 11 and from which the hot-water may be drawn through the pipe line 12, as it is well known in the art.

A plurality of bent doubled steam heating pipes generally indicated by the numeral 13 are provided in the tank each having an incoming or hot

steam pipe 14 and an outgoing returning or condensed steam pipe 15, the incoming pipes 14 being fed from the steam in a furnace 16 through the pipe line 17 and the cooled and condensed heating steam returning from the pipes 15 to the water space of said furnace 16 through the pipe line 18, as it is also well known and understood by those versed in this art. My novel heating and returning valve is indicated at 19.

My valve construction in the embodiment 10 shown in Figs. 3 and 4 may have a base element 20 secured into the front wall of the tank 10 as by the screw threads 21, through which member 20, pass the incoming or heating pipes 14 as well as the outgoing or returning pipes 15. On 15

a substantially circular flange 22 of said element 20 is secured the valve body proper 23 being divided into an upper chamber 24 and a lower chamber 25 separated and well sealed from one another. The incoming or heating pipes 14 will 20

enter the upper chamber 24 and the outgoing or returning pipes 15 will enter the lower chamber 25, as indicated in Fig. 3. The live steam pipes 17 coming from the furnace will be secured into the upper part of my valve as at 26 and will 25

normally communicate with the upper chamber 24, while the cool or condensed steam pipe 18 returning to the furnace 16 will be secured to the lower part of my valve as at 27 and will 30

communicate with the lower chamber 25. A pivoted closure flap 28 is arranged within the upper chamber 24 closing on a sealing tube seat 29 and being adapted to close or open the communication between the live steam line 17 and the chamber 24, as will be obvious. A crank 30 is provided 35

for the sealing flap 28 operated by a pivoted rod 31 on which is secured a disc 32 being acted upon by the opposing springs 33 and 34 arranged within a U shaped piece 35 having the upper and lower flanges 36 and 37 for supporting the said 40

two springs, said rod 31 being slidable through said flanges 36 and 37. An upstanding plate 38 may be secured on the upper portion of the valve flange 22, and the upper end 39 thereof carries an 45

electrical motor device 40 of any appropriate construction, several of which are known and used in this art as for instance, the J. E. Motor, manufactured by Minneapolis-Honeywell Regulator Company, which I prefer to employ in my device. A rotating arm 41 is projecting from the 50

motor device 40, operated by the same and a pivoted pin 42 thereof is engaging a boss 43 on the U shape piece 35 whereby upon the rotation of the arm 41, the rod 31 will be given a reciprocating 55

ing upward and downward movement through the dampening effect of the springs 33 and 34.

An aquastat device 44 may be secured into the front wall of the tank 10 or into any appropriate part of said tank, said device also being well known in the art as for instance, the so-called "aquastat" manufactured by the same Minneapolis-Honeywell Regulator Company, the usual cylindrical portion 45 thereof projecting into the water within the tank 10 and responding to the temperature changes thereof, as will be understood by those versed in the art. The aquastat device 44 will be appropriately electrically connected to the motor 40 as by the conductors 45a (Fig. 2) as it is also well known in this art.

The use and operation of my device will be obvious from the herein description thereof and by inspecting the drawings accompanying the same.

20 Normally, the flap 28 is entirely open being in the dotted position indicated by 28a and the live steam coming from the line 17 has a free access to the heating coils 14 in the tank 10, will heat the water herein and the cool or condensed portion thereof will return through the coils 15 and the pipe line 18. When the temperature of the water in the tank 10 reaches a certain high point to which the aquastat 44 is set, the same will make electrical connections and start electrical impulses in the motor 40 in such a manner that the push rod 31 will be pulled to an upward direction and the flap 28 will be closed upon the seat 29 thereby shutting off the incoming steam line 17 from the chamber 24 and from the heating coils 14.

40 The temperature of the water in the tank 10 may now drop and when it reaches the lower limit to which said aquastat 44 is set, the same will again operate and will send electrical currents through the motor 40, which will cause the motor to resume its motion and to push the rod 31 in a downward direction thereby opening the flap 28, that is, setting the same into the position indicated at 28a, and thereby allowing the live steam 17 to enter the heating coils and to again heat the water in the tank 10.

45 It will be seen that according to the consumption of the hot water and the feeding of cold water into the tank, my valve will alternately open and close in an automatic manner and will shut off or open the live or heating steam line, while the returning steam line from the tank will always be left open and free.

The arm 41 of the motor 40 will make a one-half turn from its lowermost position to its uppermost position when it is desired to close the flap 28, will again make a half turn in the same direction from the uppermost position to its lowermost position when it is desired to close the flap 28, its operation temporarily being stopped at either limit, as will be understood and as it is well known and used for other purposes in this art.

50 It will be understood that other controls than the electrical may be employed and that my control valve may be operated manually and that the partition therein also may be omitted, the whole valve having one single chamber to be fed by the live steam and from which the heating

5 coils originate, to which they return and from which the condensate return line will start, the flap device 28 being arranged in a similar manner to open or close the live steam feeding line. It will also be understood that my valve device 5 may be used as an independent unit in any steam, water or similar pipe line where such a valve may be adopted, and that in the present device other heating medium than steam, may be used, as, for instance, hot water.

10 It is believed from the above description that those skilled in the art will have no difficulty in understanding the construction, the method of use and operation of the device herein disclosed. The invention is of simple and practical construction and is adapted to accomplish among others all of the objects and advantages herein set forth.

15 Without further analysis, the foregoing will so fully reveal the gist of this invention that others 20 can by applying current knowledge readily adapt it for various applications without omitting certain features, that, from the standpoint of the prior art, fairly constitute essential characteristics of the generic or specific aspects of this invention, and therefore, such adaptations should and are intended to be comprehended within the meaning and range of equivalency of the following claim.

25 What I claim as new, is:

30 In a hot water heating system having a hot water tank and a source of heating fluid for said tank, a perforated member sealingly secured into the wall of said tank, a plurality of U-shaped heating tubes in said tank, one end of each tube 35 being sealingly secured into a respective upper hole in said member, and the return ends of said U-shaped tubes being sealingly secured into the respective lower holes in said member, a hollow valve body sealingly secured on said member being divided by a horizontal partition into an upper and a lower chamber, said upper holes in said member communicating with said upper chamber, said lower holes communicating with said lower chamber, an intake opening in said upper 40 chamber for the heating fluid and an exit opening in said lower chamber for the return condensate from said U-tubes, a closure device for said intake opening in said upper chamber, and means whereby said closure device is opened when the 45 temperature of the water in said tank reaches a pre-determined lower limit, and said closure device is closed upon the temperature of said water reaching pre-determined upper limit, said means comprising an extension for said perforated member, a motor carried by said extension, a crank on said motor, a U-shaped piece secured on said tank, a rod sliding through the upstanding flanges of said U-piece and having a disk secured thereon between said flanges, two coiled springs 60 between the upper and lower flanges and the center disk, respectively, said closure device being connected to said rod in such a manner that a half turn of said motor will close said device, and a continued half turn of said motor in the 65 same direction will open said closure device.

NATHAN MARCUS.
